PILING FOR THE CONSTRUCTION OF RETAINING WALLS OR THE LIKE

Ronald H. Drawsky, Walnut Creek, and David C. Thomas, Moraga, Calif., assignors to Kaiser Aluminum & Chemical Corporation

Filed June 11, 1974, Ser. No. 478,191

Term of patent 14 years

Int. Cl. D25—01

U.S. Cl. D25—74

FIG. 1 of the drawing is a perspective view of a piling for the construction of retaining walls or the like embodying our new design, and

FIG. 2 is a sectional view taken along line 2—2 of FIG. 1.

We claim:

The ornamental design for a piling for the construction of retaining walls or the like, substantially as shown.
